METHOD OF PREPARING INSOLES.

1,179,493.

Specification of Letters Patent. Patented Apr. 18, 1916.

Application filed August 4, 1911. Serial No. 642,340.

To all whom it may concern:

Be it known that I, THOMAS J. BALL, of Boston, in the county of Suffolk and State of Massachusetts, have invented certain new and useful Improvements in Methods of Preparing Insoles, of which the following is a specification.

The present invention relates to a method of preparing for reinforcing what are known commercially as "Gem" insoles. The term reinforcing is used by those skilled in the art to designate the operation of forming a bead or crimp in the reinforcing material and securing it to the insole. The reinforcing material employed is usually canvas or duck and is attached to the insole by a sticky substance which is applied to one side of the reinforcing material before it is cut into pieces of the required size.

10 The present practice is to coat the reinforcing material with the sticky substance by a distinct operation so that it may be transported in condition for use. This invention deals with such coated material, whether it 15 be coated by a distinct operation or by a coating operation performed at the time of cutting the material into strips or blanks.

20

The chief object of the present invention is to cut the aforesaid coated reinforcing material in such a way as to avoid the great waste incident to the practice hitherto followed. This practice has been to cut the sheet of reinforcing fabric into strips whose width is equal at all points and whose side 35 edges are straight. The width of such strips must, of course, be sufficient for the insoles at their widest portion, namely, the ball. The strips are then cut transversely to form separate blanks for separate soles.

40 The blanks are secured to the soles by the reinforcing operation and the excess material extending laterally from the shank on both sides is trimmed off. The quantity of excess material when the strips or blanks 45 are cut to uniform width is very great,—first, because some soles are narrower than others, and, second, because the heel and shank portions are relatively narrow. According to the method just described, only 50 the widest portion of a sole of maximum width is taken into consideration in cutting

the reinforcing material, and the loss by waste is very great. Such waste is almost entirely avoided by the method hereinafter described, because the reinforcing material 55 is cut into separate blanks of such shape and size for each sole that there is no excess material to be trimmed off.

A large sheet of reinforcing material is 60 cut along serpentine lines which correspond more or less accurately to the curvatures along the side edges of the soles. The strips produced by cutting in this manner are relatively wide at some points and relatively narrow at intermediate points, the wide portions being sufficient for the ball portions of the soles and the narrow portions being no more than necessary for the shank portions of the soles. An idea may be had of the saving made possible by the latter 65 method when it is stated that nine strips for men's soles, or thirteen strips for children's soles, may now be produced from a sheet of reinforcing material which would 70 yield not more than seven strips of sufficient width for men's soles or nine strips for children's soles if the width were equal at all points. The mere saving of canvas or duck 75 is not the greatest item of economy. The cost of the reinforcing material is greatly 80 increased by the substance with which one side is coated and by the operation of applying the coating substance. The whole cost of the prepared reinforcing material is 85 very great, and the saving made possible by the present invention is correspondingly great.

The present invention has been stated in its broad aspect, but it embraces an expedient method of actuating cutters to cause the 90 cutters to traverse serpentine lines when dividing the sheet material into strips.

The preferred method of carrying out the present invention is as follows: The prepared material, sticky on one side, is fed 95 edgewise sticky side up, and the insoles are laid with their flesh, or lipped, sides upon the sticky substance. The soles are arranged in a series of rows in such manner as to leave narrow, longitudinal strips of the sheet exposed. Preferably the edges of the rows of soles are made continuous by overlapping 100

- the heel seat of each sole on the toe of the sole next to it. This arrangement is also important as it saves canvas, it being necessary to have the reinforcing material extend only to about the breast line of the sole. The soles, also, are arranged so that their longitudinal lines are substantially parallel to the direction in which the work is fed, and the ball portion of one sole is arranged in the transverse line of the shank portion of a sole in the next row. The reinforcing material with the soles stuck to it according to the arrangement explained is fed against cutters carried by followers which are adapted to traverse the exposed strips of reinforcing material between the rows of soles. The followers are mounted so as to be laterally movable independently of each other and they are moved from side to side by the edges of the moving rows of soles, thus causing the cutters to cut in lines substantially midway of the exposed strips between the rows of soles. The serpentine strips thus produced are afterward cut transversely so as to divide them into separate blanks for the separate soles, and the canvas is then molded about the stitch-receiving ribs with which the soles are provided. The quantity of reinforcing material which may be trimmed from the sole after being molded is negligible, since the strips have been cut so that the curvature of their side edges corresponds to the curvature of the soles.
- The invention resides primarily in cutting the strips so that the curvature of the edges will be in accordance with the curvature of the soles, whether the cutting of the strips be controlled directly by the soles or whether it be performed before the soles have been attached to the reinforcing material.

Of the accompanying drawings which illustrate the preferred way in which the present invention may be practised: Figure 1 represents a perspective view of apparatus adapted to be used in practising the invention. Fig. 2 represents a top plan view of a relatively narrow sheet of reinforcing material on which a number of rows of insoles are laid, one end of the sheet material being divided to form strips. Fig. 3 represents a cross section of a portion of the sheet material with soles thereon, and an elevation of a laterally movable cutter. Fig. 4 represents a side elevation of the cutter and its movable support. Fig. 5 represents a top plan view thereof. Fig. 6 represents a horizontal section in a plane indicated in Fig. 4 by line 6-6. Fig. 7 represents a horizontal section indicated in Fig. 4 by line 7-7. Fig. 8 represents an elevation of the cutter detached from its movable support.

The same reference characters indicate the same parts wherever they occur.

In practising the present invention, as illustrated in the drawings, a sheet of reinforcing material, such as canvas or duck, is moved edgewise against one or more cutters arranged to intersect its plane. The cutters are mounted so as to be laterally movable and they are moved from side to side during the feeding movement of the work so as to curve the side edges of the strips cut in accordance with the lateral curvature of the soles which are attached to the canvas. As shown by Fig. 1, the reinforcing material, indicated at 10, is taken from a roll 11 and is passed between rolls 12 and 13. Fig. 1 includes two rolls 13 which are represented as standing at an angle one with relation to the other. Although but one roll 12 is shown by Fig. 1, because of the character of the drawing, it may be understood that there are two such rolls and that they are arranged at an angle similar to the angle of the rolls 13, also that each roll 12 coats with a roll 13. It may be assumed that the rolls 12 are driven for the purpose of feeding the sheet of reinforcing material and that the rolls 13 rest upon the work by force of gravity. The purpose in arranging the two pairs of rolls at the angle shown is to separate the strips after their severance for a purpose hereinafter explained.

The cutters are arranged to engage the work in advance of the feed roll. A cutter suitable for the purpose is shown by Fig. 8. The blade of the cutter is indicated at 14, and the cutting edge, which is V-shaped, is indicated at 15. The blade is mounted in a holder 16, hereinafter termed a follower, because it is adapted to be engaged and moved laterally by the side edges of the sole. Any desired number of cutters may be provided, depending upon the number of strips into which the reinforcing material is to be divided. The points where the cutters are intended to act upon the work are indicated in Fig. 1 at x, x, x.

Although Figs. 1 and 2 represent the sheet of reinforcing material as being divided into but four strips for four rows of soles, it is to be understood that the invention is represented in this manner only for the purpose of simplifying the drawings. The reinforcing material will, in practice, be of such width as to provide for the most economical production of strips. The soles are indicated at 20. They are attached to the reinforcing material, preferably by adhesive substance. The reinforcing material now in general use is coated on one side with suitable substance 26 which is non-adhesive under normal conditions so that the sheet may be readily unwound from the roll but which is adapted to be rendered adhesive by the application of heat or a liquid solvent.

The apparatus illustrated by Fig. 1 includes heating devices over which the sheet

material is fed to soften the adhesive substance preparatory to the attaching of the soles. The heating devices shown comprise a drum 21 and a bed 22. A gas pipe 23 extends through the drum, and a gas pipe 24 extends under the bed. The pipes are provided with orifices 25 which constitute burners. The reinforcing material is unwound from the roll in such manner that the unprepared side will engage the drum and the bed, leaving the coated side uppermost for the reception of the soles.

The soles are arranged in the relation shown by Fig. 2 upon that stretch of the reinforcing material which is passing along the bed 22. The arrangement of the soles is such as to provide longitudinal rows and transverse rows. The heel of each sole preferably overlaps the toe of the sole in the same longitudinal row, because it is not necessary to provide reinforcing material for the heel seats of the sole. Referring now to the transverse rows, it will be observed that the widest part of one sole is arranged 25 in the transverse line of the narrowest part of the adjacent sole. It is desirable to arrange alternate soles so that they extend in one direction and to arrange the intermediate soles so that they extend in the opposite direction whenever the reinforcing material may be more efficiently used as the result of such arrangement. The longitudinal rows are separated from each other so as to provide narrow, intermediate strips of exposed reinforcing material.

When the soles have been attached, they move with the reinforcing material between two coacting rolls 27 and 28 which are in advance of the cutters. The upper roll 28 is adapted to yield, but by reason of its weight it, also, is adapted to press the soles against the sheet material to make them stick more firmly. The rolls serve the additional purpose of maintaining a slight tension on that stretch of the work between them and the feed rolls 12 and 13. The followers 16 enter between the longitudinal rows of soles and move from side to side as the work advances, thus causing the cutters 50 to cut along lines substantially as shown by Figs. 1 and 2. The followers may be mounted in any desired manner in order to adapt them to be actuated in the manner explained. The preferred manner of mounting them is that shown by Figs. 3, 4 and 5. Each follower is provided with a stem 17 which is mounted in bearings in an arm 18. The arm is connected to a suitable bracket 55 29 by a pivot member 19. The bracket is mounted upon a rod 30 arranged to extend transversely over the work. The several brackets 29 for the several cutters may be fastened at the desired position upon a rod 30, each bracket being provided with a set-screw 31 for this purpose. The arms 18 are

free to swing about the pivots 19, and the followers are adapted to turn about their stems 17. Each arm is preferably provided with a roll 32 for engaging an arm 33 on the bracket 29 for the purpose of sustaining any stress upon the arm, so as to prevent the pivot 19 binding in its bearing. Each follower is normally held in one position by a spring 34. In order to limit oscillatory movement of the follower about its stem 17, the arm 18 is provided with a lip 35 adapted to be engaged by projections such as pins 36 inserted in the follower as shown by Fig. 7.

The cross section of an insole is shown by Fig. 3. The edge of the sole is split to provide a stitch-receiving rib 37 and a feather 38. Each follower is provided with lips 39 which extend laterally, one from each side. The lips are adapted to lie between the feather 38 and the reinforcing material 10, and their function is to keep the work and the cutter in operative relation.

The work, after being divided into strips, passes between the rolls 12 and 13. The strips become spread apart laterally by reason of the angular arrangement of the rolls and in this way the liability of the strips becoming overlapped and stuck to each other is avoided. A board or delivery table (not shown) may be arranged to receive the work 95 from the rolls 12 and 13. The strips are afterward cut transversely, across the toe of each sole, to provide a separate reinforcing blank for each sole, and thereafter the canvas blanks are then molded upon the soles 100 and trimmed if necessary in the usual manner.

The knife 14 in making the sinuous cuts, is guided by means of the lips 39 which contact with the lip 37, and also by a contact 105 of the follower 16 with the feather 38. Therefore, the knife is guided by either the lip 39 or the follower 16. In the claims the term "marginal portion" of an insole refers to the rib 37 as well as to the feather 38, 110 since these portions of the insole serve as a guide or form a cam path to control the course of the cutter 14.

I claim:

1. The method of cutting sheet material 115 for reinforcing insoles, consisting in relatively moving the material and a cutter to advance the point of operation of the cutter upon the material in the direction of the length of a series of insoles positioned end 120 to end upon the material, and moving the cutter transversely of the relative movement of the material and cutter in accordance with lateral curvatures of the series of insoles.

2. The method of cutting sheet material for reinforcing insoles consisting in drawing the material in a continuous rectilinear path edge-wise against a cutter, positioning insoles in a row upon the material before it 130

reaches the cutter, and moving the cutter relative to the movement of the material to cut a series of reverse curves in accordance with lateral curvatures of the insoles in the 5 row.

3. The method of cutting sheet material for reinforcing insoles consisting in causing a relative feeding movement of the material and a plurality of cutters in a continuous 10 rectilinear path, attaching insoles in rows upon the material, and reciprocating the cutters between the rows of insoles transversely of the relative movement whereby a series of cuts are produced having reverse curves 15 in accordance with lateral curvatures of adjacent rows of insoles.

4. The method of preparing insoles for reinforcement comprising giving the reinforcing material a continuous rectilinear 20 feeding movement against a series of cutters, attaching insoles for simultaneous movement with the material, and cutting the material from end to end along lines determined by lateral curvatures of the marginal 25 portions of the insoles.

5. The method of preparing insoles for reinforcing, consisting in placing the same in rows end to end upon a sheet of adhesively coated reinforcing material, rendering the material adhesive to secure the insoles, and utilizing the rows of insoles as a guide for cutting the material into strips along reversely curved lines simulating lateral curvatures of the rows of insoles.

6. The method of preparing insoles for reinforcing, consisting in sticking a series of insoles in rows to a sheet of reinforcing fabric, then feeding the series of insoles while stuck to the fabric, and thereafter cutting the sheet into strips along lines extending substantially equidistant between adjacent rows of insoles, substantially as described.

7. The method of preparing insoles for reinforcing, consisting in sticking insoles end to end in a series of rows to a sheet of reinforcing fabric and cutting the sheet continuously from end to end into strips along reversely curved lines extending substantially equidistant between adjacent rows of insoles, substantially as described.

8. The method of cutting sheet material for reinforcing insoles comprising, positioning the insoles on the material in rows 55 with the ball portion of the insole in one row opposite the shank portion of the insole in an adjacent row, feeding the material against a cutter, and moving the cutter relatively to the line of feed to form a 60 serpentine path which is approximately determined by lateral curvatures of opposed marginal portions of the insoles in adjacent rows.

9. The method of preparing reinforcing 65 material for insoles consisting in feeding a

reinforcing material with an adhesive side thereon against a cutter treating the reinforcing material to make it adhesive, placing insoles upon the adhesive material, pressing the insoles to secure them to the material, and cutting the material in a path determined by marginal portions of the adhering insoles. 70

10. The method of preparing insoles for reinforcing consisting in feeding a sheet of sticky reinforcing fabric with rows of insoles adhering thereto, dividing the fabric between the rows into strips having edges of serpentine outline, and then laterally forcing apart the strips so cut to prevent entangling, substantially as described. 75

11. The method of preparing insoles for reinforcing consisting in sticking insoles end to end in a series of rows to a sheet of reinforcing fabric, alternate rows having the toes of the insoles pointed in opposite directions, and then cutting the sheet into strips along lines lying between the rows of insoles, and simulating lateral curvatures of their marginal portions, substantially as described. 80

12. The method of preparing insoles for reinforcing consisting in sticking insoles end to end in a series of rows to a sheet of reinforcing fabric, dividing the fabric into strips having edges of serpentine outline, by cutting between the rows, and then dividing the strips into single blanks by severing them transversely at one end of each insole, substantially as described. 85

13. The method of preparing insoles for reinforcing consisting in sticking insoles to a sheet of reinforcing fabric arranged heel to toe in a series of rows each heel overlapping the toe of the next adjacent sole in the row, dividing the fabric into strips by cutting between the rows, and then cutting the strips transversely into single blanks across the toe of each insole, substantially as described. 95

14. The method of preparing insoles for reinforcing consisting in feeding forward a sheet of adhesively coated reinforcing fabric, sticky side up, then laying lipped insoles, lip side down, on said fabric, heel to toe in a series of rows, insoles in adjacent rows having balls opposite shanks, leaving exposed a sinuous strip of fabric between adjacent rows, then cutting the fabric into strips between adjacent rows simultaneously on a serpentine line, then forcing apart the strips so cut, laterally, to prevent entangling, and then severing the strips transversely into single blanks, substantially as described. 110

15. The method of preparing sheet material for reinforced insoles comprising, relatively moving a web of reinforcing material and a series of cutters arranged across the web to sever the web of reinforce- 115 120 125 130

ing material into two or more strips, and moving the adjacent cutters alternately toward and from one another transverse to the line of relative movement of the web and 5 cutters to make each pair of cuts alternately diverge and converge.

In testimony whereof I have affixed my signature, in presence of two witnesses.
